UNITED STATES PATENT OFFICE.

JOHN H. ALLEN, OF VERONA, NEW JERSEY.

RAIL-JOINT.

No. 025,701.

Specification of Letters Patent.

Patented June 22, 1909.

Application filed December 28, 1907. Serial No. 408,423.

To all whom it may concern:

Be it known that I, JOHN H. ALLEN, a citizen of the United States, residing at Verona, in the county of Essex and State of New Jersey, have invented certain new and useful Improvements in Rail-Joints, of which the following is a specification.

This invention relates more particularly to that class of railway joints known as offset or compromise joints, and the objects of the invention are to provide a connecting plate for such joints which can be simply and cheaply produced by casting; to secure maximum strength and durability of the joint; to provide a construction which shall not interfere with the application of the connecting plates to the rail ends, and to obtain other advantages and results as may be brought out in the following description.

Referring to the accompanying drawings, in which like numerals of reference indicate the same parts in the several figures, Figure 1 is an end view of a joint of my improved construction, the rail being shown in section; Fig. 2 is a side elevation of the joint; and Fig. 3 is an underneath view; Fig. 4 is an end view of a joint of my improved construction in which the connecting plates are slightly modified; Fig. 5 is a side elevation of the joint shown in Fig. 4, and Fig. 6 is an underneath view of the same.

In said drawings, and particularly Figs. 1, 2 and 3 thereof, 1 indicates the larger of two rails coming together in an offset joint, said rail having the head 2 with upper tread surface 3 and lower upwardly and outwardly inclined lateral bearing surfaces 4, 4, a vertical web 5 perforated to receive the fastening bolts of the joint, and lateral base flanges 6, 6, each providing an upper outwardly and downwardly inclined bearing surface 7, 11 indicates the smaller of the two rails forming the offset joint, and which also has all the features just described in connection with said larger rail 1 and which are indicated on the smaller rail 11 by reference numerals 12 to 17 inclusive.

My improved connecting plates are used in pairs, a right and a left for each joint, arranged on opposite sides of the rail ends; aside from this their construction is just alike and a detail description of one will suffice for the other.

The connecting plate 20 has a main vertical or upright portion 21 adapted to lie between the heads and base flanges of the rails

and forming at one end portion of its upper edge an inwardly beveled bearing 22 to engage the under surface 4, of the head of the larger rail, and at the other end portion of its upper edge a similar but higher bearing 23 for the head 12 of the smaller rail. At the lower edge of the end portion for the larger rail is an outwardly projecting doubled flange 24 adapted to receive the base flange 65 of the rail, and at the other end portion is a similar doubled flange 25 enough higher up to correspondingly receive the base flange of the smaller rail.

It will be understood that the main upright portions of the connecting plates are perforated as at 26, 46, respectively, in alignment with perforations of the rails, so that bolts 9 may bind the whole firmly together. Furthermore, the upper edge bearings of the connecting plates flare upwardly oppositely outward, as shown, in the usual manner, and their doubled bottom flanges wedge onto the base flanges of the rails without the main upright portions of the fish plates approaching the vertical web of the rail, so that a powerful wedging effect is obtained by tightening up the bolts.

It will be understood that the greatest strain under a train passing over this joint occurs just as the wheels pass from one rail to the other, and in order to take this strain I provide at the under surface of the lower walls 27 and 28 of the doubled flanges 24 and 25 of the connecting plate, and at the middle of the length of the plate, the reinforcement next to be described.

At the inner edge, or near the inner edge, of said lower walls 27 and 28 is formed or cast an integral downwardly extending girder 29, which extends longitudinally of the connecting plate for a short distance on both of the said end portions of different height, as shown. From the ends of said girder 29, ribs 30 extend transversely of the connecting plate to the outer edge of the doubled flange 24, the lower edges of said ribs 30 sloping outward from the full height of the vertical girder 29 to nothing. Preferably these ribs 30 stand at right angles to the length of the connecting plate and are inclined downwardly toward each other or converge, as shown in Fig. 2 especially, so that they go between two adjacent ties with the greatest ease and facility. It will be understood that the whole strengthening means described, consisting of girder 29 and

ribs 30, lies between two adjacent ties (not shown), to which the rail joint is secured by means of spike seats 31, 31, on the edges of the doubled flanges 24 and 25 of the connecting plates.

The opposite connecting plate 40 from the one just described is of the same construction except reversed in positions of its parts to fit the opposite side of the rail, said parts 10 of this connecting plate being marked with reference numerals consecutively from 41 to 51 to correspond with the parts marked with reference numerals 21 to 31 on the connecting plate 20.

15 Under some conditions, those portions of the under wall of the doubled flanges 24 and 25 (or 41 and 45) of the connecting plate, outside the portion included by the girder 29 and ribs 30, may be cut away or omitted, as 20 in Figs. 4-6, and a lighter and cheaper joint secured. In said figures, 60 indicates one of the connecting plates and 70 the other, each having a vertical portion 61 (or 71), stepped at its upper edge to receive the different rails.

25 At the ends of the plate, said vertical portion 61 (or 71) is provided at its bottom with simply downwardly and outwardly inclined flanges 62 and 63, (or 72 and 73), which seat upon the top of the base flanges of the rails, 30 as is common in angle pieces, and are notched at their outer edges to receive the spikes, as at 68 (or 78). The middle portion of the length of each connecting plate, however, has the same sort of a doubled flange 64 (or 35 74) which was above described in connection with Figs. 1, 2 and 3, and which incloses the base flanges of the rails at and adjacent to their meeting ends, as shown. The lower wall 65 (or 75) of this doubled portion 64 (or 40 74) is furthermore provided at its inner edge with a vertical girder 66 (or 76), and from the ends of which ribs 67, 67 (or 77, 77) preferably slope outwardly to the double edge of the flange 64 (or 74).

45 It will be understood that my improved connecting plates are preferably cast, and the construction described is one which to the greatest extent facilitates such casting. For instance, the strengthening girder on the 50 under side of the doubled member of the connecting plate is placed at the inner edge of the same or away from the thick doubled edge of the base flange, in order to secure an equal distribution of the metal and prevent 55 such a shrinkage in cooling as will pull down the vertical portion of the plate and cause a depression of the upper bearing surfaces thereof just where the meeting extremities of the rails rest. In many such ways, my 60 improved construction of connecting plate is especially well adapted for its purpose.

Having thus described the invention, what I claim as new is:

1. A connecting plate for rail joints, comprising a main portion having an upright

web adapted to bear at its upper and lower edges against the head and base flange of a rail and having a doubled flange portion adapted to inclose the base flanges of the meeting ends of the rails, a depending girder on the under side of said doubled portion at a distance from the outer edge of the same and extending longitudinally of the connecting plate, and ribs extending from said girder transversely of the connecting plate toward its outer edge, the under wall of the doubled portion extending across the space inclosed by said girder and ribs.

2. A connecting plate for rail joints, comprising a main portion having an upright web adapted to bear at its upper and lower edges against the head and base flange of a rail and having a doubled flange portion adapted to inclose the base flanges of the meeting ends of the rails, a downwardly projecting girder on the under side of said doubled flange at a distance from the outer edge of the same, and ribs extending transversely of the connecting plate from said girder toward the outer edge of the plate, said ribs sloping at their lower edges from the girder toward the bottom of the said doubled portion of the connecting plate, the under wall of the doubled portion extending across the space inclosed by said girder and ribs.

3. A connecting plate for rail joints, comprising a main portion with vertical web and outwardly extending doubled lower flange, a downwardly projecting girder on the under side of said doubled flange at a distance from the outer edge of the same, and ribs extending transversely of the connecting plate from said girder to said outer edge and being inclined at their lower edges from the lower edge of the girder to the outer edge of the doubled portion, the under wall of the doubled portion extending across the space inclosed by said girder and ribs.

4. A connecting plate for rail joints, comprising a main portion with a vertical web and an outwardly extending doubled lower flange, a depending girder on the under side of said doubled portion at a distance from the outer edge of the same and extending longitudinally of the connecting plate, and ribs extending from said girder transversely of the connecting plate toward the outer edge of the same and being inclined downwardly from the doubled portion toward each other or converging, the under wall of the double portion extending across the space inclosed by said girder and ribs.

5. A connecting plate for rail joints, comprising a main portion having an upright web adapted to bear at its upper and lower edges against the head and base flange of a rail and having a doubled flange portion adapted to inclose the base flanges of the meeting ends of the rails, a depending girder on the under side of said doubled portion at

5 a distance from the outer edge of the connecting plate and extending longitudinally of said plate, and ribs extending from said girder transversely of the connecting plate toward the outer edge thereof, said ribs being inclined downward from the said doubled portion or converging toward each other and sloping at their lower edges from the 10 said girder toward the bottom of the doubled portion, the under wall of the doubled portion extending across the space inclosed by said girder and ribs.

6. A connecting plate for rail joints, comprising a main portion with a vertical web 15 and an outwardly extending doubled lower flange, a downwardly projecting girder on the under side of said doubled flange at a distance from the outer edge of the connecting plate and extending longitudinally thereof, and ribs extending from said girder to the outer edge of the connecting plate, said ribs converging downwardly from the doubled portion and having their lower edges sloping 20

from the lower edge of the girder to the outer edge of said doubled portion, the under wall 25 of the doubled portion extending across the space inclosed by said girder and ribs.

7. A connecting plate for rail joints, comprising a main portion with an upright web and an outwardly extending doubled lower flange, a downwardly projecting girder on the under side of said doubled flange at a distance from the outer edge of the same extending longitudinally of the connecting plate, and ribs extending from said girder transversely of the connecting plate toward the outer edge of the same, the under wall of the doubled portion extending across the space inclosed by said girder and ribs and being discontinued or cut away outside said girder 40 and ribs.

JOHN H. ALLEN.
